URINARY DEVICE

Lee K. Breece, Jr., San Pedro, Calif., assignor, by mesne assignments, to Resiflex Laboratory, Los Angeles, Calif., a corporation of California

Filed Mar. 1, 1963, Ser. No. 262,084

2 Claims. (Cl. 128—295)

This invention relates generally to a urinary device and, more particularly, to a urinary device adapted for use by adult females who may be incontinent or have difficulty in controlling discharges from the bladder.

The containment or collection of an involuntary discharge of urine by a female has been the subject of several prior proposed devices which were externally applied and covered uro-genital organs in an attempt to direct such flow into a suitable receptacle or collection bag, either carried on the leg or placed adjacent the patient if the patient was bedridden. Such prior devices could be readily associated with an immobilized patient and, in general, were satisfactory. However, when a patient was only partially immobilized, was capable of sitting up or changing position in bed, or was an ambulatory patient, such prior devices often shifted due to such movement of the patient and body pressures created by such movement. In such instance, capture and control of the discharge was incomplete and not satisfactory. In general, such prior devices presented several disadvantages or difficulties as incomplete, non-positive sealing around the urethral orifice, discomfort in wearing such prior devices, change in position of such devices when the patient moves, bulkiness of external padding sometimes used. Lack of capability to maintain a positive sealing relation with the urethral orifice during various movements of the body of the patient was perhaps the major disadvantage.

The present invention contemplates essentially an internal type of female urinary device which is so constructed and arranged that it obviates the disadvantages of prior proposed external type devices and those internal type devices which utilize other body cavities for maintaining position of the urinary device, such as Patent 2,483,079. The present invention contemplates a urinary device which includes a deformable resilient, flexible tubular fitting or member adapted to be internally inserted between labia of the vulva for sealing engagement under slight pressure with surfaces surrounding the urethral orifice and wherein such tubular member is retained in position without discomfort to a mobile or immobilized patient. The tubular member is short in length, readily laterally deformable at its inner end portion and has an outer end portion which is adapted to be releasably connected to a support means. The support means generally comprises a flexible resilient, triangularly shaped, support member having side walls of selected configuration for engagement with external surfaces of the labia of the vulva. The tubular member communicates through a port in the support member with a suitable drain tube which may conduct discharges to a suitable bag or receptacle of selected type.

The primary object of the present invention therefore is to disclose and provide a novel urinary device adapted for use by females for directing urine evacuations to a suitable receptacle.

An object of the invention is to disclose and provide a novel urinary device which can be worn without discomfort and which retains its position during usual movements of the body of a patient.

Another object of this invention is to disclose and provide a urinary device for incontinent patients which is simple and inexpensive.

A further object of the invention is to disclose and

2

provide a urinary device for incontinent patients which can be easily and conveniently associated with the uro-genital organs of a patient.

Still another object of the invention is to disclose an internal type urinary device having means to effect a positive, slight pressure seal about a urethral orifice without discomfort to the patient and to maintain such seal during various movement of the patient's body.

A further object of the invention is to provide a sanitary, readily cleanable, female urinary device.

A still further object is to disclose such a device which is readily adaptable to fully incontinent patients and which may be simply modified for use by slightly incontinent patients.

Many other objects and advantages of the present invention will be readily apparent from the following description of the drawings in which exemplary embodiments of this invention are shown.

In the drawings:

FIG. 1 is a perspective view of a urinary device embodying this invention.

FIG. 2 is an enlarged fragmentary top plan view of a support means and tubular member embodying the invention as shown in FIG. 1.

FIG. 3 is a longitudinal sectional view taken in the plane indicated by line III—III of FIG. 2.

FIG. 4 is a transverse sectional view taken in the plane indicated by line IV—IV of FIG. 2.

FIG. 5 is a transverse sectional view taken in the same plane as FIG. 4 showing a modification of the device for slightly incontinent patients.

In FIG. 1, a urinary device embodying this invention is generally indicated at 10. Device 10 generally comprises a support means 11 and a tubular means such as tubular member or fitting 12 carried by the support means.

The support means 11 may be suspended from a waist belt 14 by a pair of front straps 15 and a back strap 16. The front straps 15 may be attached by suitable fasteners 17 to the front of the support means at corners thereof and may extend upwardly along the groin at the depression between the thigh and the lower abdominal portion of the body. For this purpose, the upper ends 18 of straps 15 may be adjustably located and fastened to the waist belt 14 by suitable spaced fastener elements 19. The back strap 16 similarly has an upper end 20 adjustably attached to the waist belt 14 at suitably spaced fasteners 21. It will be understood that the fasteners 17, 19 and 21 may be of any well known snap-type or other type of fasteners.

The device 11 may be of generally triangular shape and may have a wide front top portion 23 adapted to be placed over and to cover the lower pubic region. Member 11 tapers toward the rear to a back end 24 suitably configured, in this example, rounded and providing sufficient space for fastener 25 for back strap 16, the fastener 25 being of similar type as fasteners 17.

The support member 11 may be made of any suitable impervious, flexible, pliant material such as latex, rubber, synthetic plastic materials capable of being molded and presenting a relatively soft, non-irritating, yieldable surface.

The support member 11 also includes a preferred, pre-molded, centrally disposed elongated, ovate means 27 comprising side walls 28 of somewhat sigmoidal configuration integrally joined with support member 11. The walls 28 include a central portion 29 normally disposed generally parallel to the main wall 30 of the support member 11 and terminate in the outwardly directed flange portions 31 extending over a section of the central portions 29. The flange portions 31 provide a top skin engaging sur-

face 32 adapted to seat against skin areas as later described.

The preformed main wall 30 of support member 11 includes an inclined offset ported, tubular member mounting section 34 providing a slanted recess 35 on the front face 36 of wall 30 and a slanted embossment 37 on the back or internal face of wall 30. The embossment 37 is adapted to be received within the slight perineal depression in the patient's body and serves to assist location and positioning of the device. The inclined offset section 34 has a port 38 having an axis disposed at an angle to the main wall 30 so as to direct such axis generally along and between the legs of the patient.

Tubular member 12 is carried by support member 11 at port 38. Tubular member 12 may be made of material similar to support member 11 and may be preformed or premolded to an initial selected shape and configuration. In this example, tubular member 12 includes an outer circular end portion 40 receivable within port 38. In this example, means for releasably securing end portion 40 in port 38 may comprise a preformed external circular attachment rib 41 on end portion 40 and receivable within a corresponding annular groove or recess 42 provided in the edge face of port 38. Since the material of tubular member 12 is flexible and preformed to this shape, the outer end portion 40 may be inserted in port 38 and then permitted to expand so that the annular rib 41 firmly interengages and interlocks with annular groove 42. The outer end face of end portion 40 may be flush with the front surface 36 of main wall 30 of the support member.

Above end portion 40 tubular member 12 may include a central preformed wall 43 of bellows, accordion, or transversely convoluted configuration. Wall 43 changes in cross-sectional configuration from the circular configuration of outer end portion 40 into an ovate configuration with the major diameter extending longitudinally of support member 11. Wall 43 extends above the flange surface 32 and terminates in an ovate outwardly directed flange or lip 44 of slightly thicker section than the section of wall 43. The inner end portion 45 of tubular member 12 with outwardly extending lip 44 which provides a skin engaging surface 46 is thus sufficiently flexible and deformable to permit change in shape under slight pressures while maintaining its normal configuration when not under pressure.

The tubular member 12 thus provides a passageway 48 adapted to vary in cross-sectional configuration while maintaining an open passageway. Passageway 48 communicates with a suitable tubular connector means 50 having a passageway 51 and releasably connected to the outer end portion 40 within port 38. In this example, such releasable connection is readily made by the provision of an annular recess 52 in the internal surface of end portion 40 opposite rib 41 and the interlocking reception therein of a radially outwardly directed bead 53 provided at the inner end 54 of the connector means 50. The connector means is not shown in detail since it may be of any suitable type of connector made of plastic material and having at its outer or front end means for connecting to a flexible tube 55 for conducting fluid discharges to either a stationary bottle or receptacle alongside a bed or to a suitable urine collection bag strapped to the leg of the patient. Such collection bags may be of different construction and is not shown herein. Preferably, the connecting means 50 includes a check valve construction (not shown) which will permit discharged fluid to pass into the tube 55 and which will prevent back flow of such fluid. Such check valves are well known and in this instance may include a simple flap-type valve inserted into the connecting means and secured therein by well known means. Since the support member 11 and tubular member 12 are flexible and made of latex or the like, it will be readily apparent that the relatively rigid inner end 54 of the connecting means may be inserted

into the end portion 40 of member 12 and end portion 40 will resiliently grasp and hold the connector means 50.

When device 10 is associated with the patient's body, belt 14 is placed around the waist of the patient with the upper end 20 of the back strap 16 unfastened therefrom. The front straps 15 may be readily adjusted to the groin depressions and the support member 11 located adjacent the lower pubic regions. The tubular member 12 is then slightly laterally deformed so that the flange or lip 44 may be inserted within the labium minus of the vulva to bring the slightly widened surfaces 46 into contact with internal skin surfaces surrounding the urethral orifice. Since such surfaces are normally moist and since the material of the tubular member is flexible and deformable and soft, the surfaces 46 provide a seal around the urethral orifice. The labium minus, after insertion of the tubular member 12, may partially overlap the flange 44 and lie between flange 44 and the flange 31 on the support member 11. The surfaces 32 on flange 31 of the elongated configuration of the side walls 27 are adapted to contact and engage external surfaces of the labium majus. The arrangement of the tubular member and side walls 27 is so designed that the normal position of the labium minus and labium majus will be virtually undisturbed when the device 10 is worn by the patient.

It should be noted that the sigmoidal configuration of the side walls 27 provides a construction which is adapted to apply a very slight pressure to the external surfaces of the labium majus and thus effect an external seal therewith. Similarly, the bellows-type or convoluted wall 43 of tubular member 12 provides a resiliency in the construction of the tubular member which imparts a very slight pressure to the flange 44 to effect a positive seal against skin surfaces surrounding the urethral orifice. It will be understood that the slight pressures referred to are insufficient to cause irritation of the skin surfaces and discomfort to the patient.

When the device 10 is properly adjusted and positioned on the patient's body, the perineal offset 34 will be located at the perineum of the patient's body and will locate and maintain the tubular member 12 in proper longitudinal relationship with respect to the vulva. Moreover, the interaction and engagement of the labium majus and labium minus with the side walls 27 and tubular member 12, respectively, also serve to maintain the tubular member 12 in its proper location with respect to the urethral orifice. When the device 10 is properly fitted and adjusted to the body of the wearer, the back strap 16 may be connected with the waist belt 14 and the front straps 15, back strap 16 adjusted for comfort.

It will thus be apparent that in the case of ambulatory patients, the device 10 is so supported and held in relation to the urethral orifice that even though the patient engages in usual normal body movements such as walking, sitting down, lying down, bending over and the like, the tubular member 12 will maintain its sealed relation with the urethral orifice and involuntary discharges will be directed through the passageways 48 and 51 to the tube 55 to an associated leg bag.

It is understood that the tubular member 12 and the length and width of the side walls 27 may be of different size and of slight variations in shape. The sigmoidal wall configuration of side walls 27 may be modified as long as a skin engaging surface 32 of desired width and configuration is afforded.

It is normally desired that the tubular member 12 be provided with an outer end portion 40 of circular form to facilitate connections with a connector such as 50. The remainder of the tubular member 12 may vary in cross-sectional configuration to include cylindrical, frusto-conical, ovate, and other suitable desired forms which may provide a tubular member adapted to impart through the construction and material of the member, a slight pressure against skin surfaces and adaptability to accom-

modate any slight shifting, turning or twisting of the patient's body during movement.

FIG. 5 shows the device 10 modified and adapted for use by patients only slightly incontinent. In such instances, the wearing of a leg bag or the connection of device 10 to a fluid collecting receptacle is usually not necessary. Device 10 may be modified by removing tubular member 12 and connector 50 from the part 38 in the main wall 30 of the support member 11 and inserting a plug means such as a suitable circular plug 60 of an impervious material slightly stiffer than the soft, flexible material of the support member 11. Plug 60 includes an annular rib 61 on its circumferential edge face 62, the annular rib 61 being received within the annular groove 42 provided in the side member 11. The plug is thus interlocked and grapsed by the port margins of wall 30.

A pad 64 is provided with a configuration generally corresponding to the configuration of the chamber or cavity 65 defined by the side walls 27 and the overlying portions 28 of the side walls. Pad 64 is thus readily held within the side walls 27. Pad 64 may be made of any suitable soft, absorbent material in order to absorb the slight discharges of the patient. The pad 64 may also be treated with suitable well-known sanitizing and deodorant agents.

Removal of the pad 64 and plug 60 permits the support means to be quickly and readily adapted with a tubular member 12 and connector 50 in the event the patient becomes more incontinent.

It will be understood that various modifications of the construction of the tubular member 12, the support means 11 may be made within the spirit of this invention and all such modifications and changes coming within the scope of the appended claims are embraced thereby.

I claim:

1. A urinary device for a female comprising: a nor-

mally upstanding resilient open ended tubular member having an inner end portion laterally and longitudinally resiliently deformable and an outer end portion, said inner end portion having an outwardly directed peripheral lip adapted to be internally received between labia minora for sealingly engaging surfaces surrounding a urethral orifice; and support means connected to the outer end portion of the tubular member and having an ovate flange for engaging external surfaces of the labia majora to retain said tubular member in position with respect to the urethral orifice.

2. A female urinary collection device comprising: a pliant support means provided with a port; an axially compressible tubular-like open-ended fitting carried by the support means in communication with said port and having an inner deformable end adapted to be internally received and held between labia minora and to sealingly surround a urethral orifice; said pliant support means including a resilient flange with surface to engage labia majora for retaining the position of said fitting and means connected to the support means for conducting fluid from the port to a collection receptacle.
